ABSTRACT

A *chrysanthemum* plant named 'Katelli' characterized by its medium sized blooms with orange ray florets and prolific branching; natural season flower date September 13–20; blooming for a period of 5 weeks.

3 Drawing Sheets

1

BACKGROUND OF THE INVENTION

'Katelli' is a product of a breeding and selection program for outdoor pot mums (garden mums) which had the objective of creating new *chrysanthemum* cultivars with a decorative type flower, a natural season flower date around September 13–20; blooming for a period of 5 weeks. The new plant of the present invention comprises a new and distinct cultivar of *chrysanthemum* plant 'Katelli' is a seedling resulting from a crossing program, which was set up by a previous breeder, and which records are unknown to the inventor. The new and distinct cultivar was discovered and selected as a flowering plant by Mark Roland Boeder on a cultivated field in Rijsenhout, The Netherlands in 2001. The first act of asexual production of 'Katelli' was accomplished when vegetative cuttings were taken from the initial selection in 2001 in a controlled environment in Rijsenhout, The Netherlands, and further propagated at this location. The new cultivar has been found to retain its distinctive characteristics through successive propagations.

BRIEF DESCRIPTION OF THE DRAWINGS

The present invention of a new and distinct variety of *chrysanthemum* is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the foliage of the new cultivar.

DESCRIPTION OF THE INVENTION

This new variety of *chrysanthemum* is of the botanical classification *Chrysanthemum morifolium* L. The observations and measurements were gathered from plants grown out door in Rijsenhout, The Netherlands under natural day length and temperature and planted in week 24 in 2004. The natural blooming date of this crop was September 13–20 (week 38). The average height of the plants was 38 cm. No growth retardants were used. No tests were done on disease

2

or insect resistance or susceptibility. No tests were done on cold or drought tolerance. This new variety produces medium sized blooms with orange ray florets and a dark red center blooming for a period of 5 weeks.

From the cultivars known to inventor the most similar existing comparison to 'Katelli' is 'Mars' (U.S. Plant Pat. No. 14,678). When 'Mars' and 'Katelli' are being compared the following differences are noticed: The differences of 'Mars' and 'Katelli' are (1) Color ray-florets. The ray-florets of 'Katelli' are more tending towards bronze than of 'Mars'. (2) Natural response time. Under natural conditions, 'Katelli' flowers earlier than 'Mars'.

The following is a description of the plant and characteristics that distinguish 'Katelli' as a new and distinct variety. The color designations are taken from the plant itself. Accordingly, any discrepancies between the color designations and the colors depicted in the photographs are due to photographic tolerances. The color chart used in this description is: The Royal Horticultural Society Colour Chart, edition 1995.

TABLE 1

Botanical Description of <i>chrysanthemum</i> plant 'KATELLI'	
<u>Bud</u>	
Size	Small; cross-section 0.5 cm, height 0.8 cm
Outside Color	Yellow-green 145D
30 Involucral bracts	2 rows, length 7 mm, width 3 mm
Involucral bracts among disc-florets	Not present
Involucral bracts color	Green 138B
<u>Bloom</u>	
35 Type	Decorative
Height	1 cm
Size	Medium
Fully Expanded	4.5 cm
Peduncle length	6 cm
Peduncle color	Green 143C
Number of blooms per branch	Approx. 10 blooms per branch
40 Performance on the plant	5 weeks

TABLE 1-continued

Botanical Description of <i>chrysanthemum</i> plant 'KATELLI'	
Seeds	Produced in small quantities, ovate grey-brown 199A, 1½ mm in length.
Fragrance	Typical <i>chrysanthemum</i> , slightly
<u>Color</u>	
Center of the flower	Immature Greyled-red 178A Mature Greyled-orange 173C
Color of upper surface of the ray-florets	Greyled-orange 163A to Greyled-yellow 162A
Color of the lower surface of the ray-florets	Greyled-orange 167A
Tonality from Distance	A garden mum with orange flowers and a dark red disc
Discoloration to color	Greyled-orange 163A to Greyled-yellow 162A
<u>Ray florets</u>	
Texture	Upper and under side smooth
Number	240-250
Cross-section	Flat
Longitudinal axis of majority	Straight
Length of corolla tube	0.8 cm
Ray-floret margin	Entire
Ray-floret length	2 cm
Ray-floret width	0.5 cm
Ratio length/width	High
Shape of tip	Rounded
Disc florets	Absent
Receptacle shape	Conical raised
<u>Reproductive Organs</u>	
Stamen	Absent
Pollen	Not produced
Styles	Thick
Style color	Yellow 13A
Style Length	4 mm
Stigma color	Yellow-green 144A
Stigma Width	1 mm
Ovaries	Enclosed in calyx
<u>Plant</u>	
Form	Grown as a spray type potmum, outdoor mounded and round
Growth habit	Spherical shape
Growth rate	High
Height	38 cm
Width	40 cm
Stem Color	Greyled-brown 199C
Stem Strength	Medium
Stem Brittleness	Not brittle

TABLE 1-continued

Botanical Description of <i>chrysanthemum</i> plant 'KATELLI'	
Stem Anthocyanin Coloration	Absent
Internode length	1.5-2 cm
Length of lateral branch	From top to bottom 18 cm
Lateral branch color	Yellow-green 148B
Lateral branch, attachment	Medium
Branching (average number of lateral branches)	Good with 7-8 breaks after pinching
Natural season blooming date	September 13-20
<u>Foliage</u>	
Leaf color	Upper side Green 137A Lower side Green 138A-138B
Color midvein	Upper side Yellow-green 147D Lower side Yellow-green 147D
Size	Small; length 3-5 cm, width 2-3 cm
Quantity (number per lateral branch)	25
Shape	Obovate
Texture upper side	Glabrous
Texture under side	Pubescent
Venation arrangement	Palmate
Shape of the margin	Serrated
Shape of Base of Sinus Between Lateral Lobes	Rounded
Margin of Sinus Between Lateral Lobes	Diverging
Shape of Base	Obtuse
Apex	Mucronulate
Petiole length	0.8-1 cm
Petiole color	Yellow-green 147D

TABLE 2

Differences with the comparison varieties

	'Katelli'	'Mars'
Color upper surface ray-florets	Greyled-orange 163A to Greyled-yellow 162A	Yellow-orange 22B
Start blooming date (planted in week 24)	Week 38	Week 41

I claim:

1. A new and distinct variety of *chrysanthemum* plant as described and illustrated.
